UNITED STATES PATENT OFFICE.

HANS v. SCHLEINITZ, OF HANOVER, GERMANY.

DEVICE FOR LANDING OR BERTHING AIRSHIPS.

1,119,646.

Specification of Letters Patent.

Patented Dec. 1, 1914.

Application filed July 7, 1913. Serial No. 777,765.

To all whom it may concern:

Be it known that I, HANS v. SCHLEINITZ, a citizen of the German Empire, residing at Hanover, in the Kingdom of Prussia, German Empire, have invented new and useful Improvements in and Relating to Devices for Landing or Berthing Airships, of which the following is a specification.

This invention relates to a device for landing or berthing air-ships, the device being of a type wherein the air-ship is secured upon a car or cars, with the assistance of easily operated means, and is supported in a resilient but safe manner upon said car or cars.

A constructional example of the invention is illustrated in the accompanying drawing.

It is to be assumed that the cars, adapted to receive the air-ship, are rotatable in the known manner on a turntable, which latter is provided with an extensible pivoted support for the anchoring cable. This support is adapted to prevent the head of the airship from being pressed on the ground by the wind, and also for the purpose of bringing the airship to the correct level so that it can be fastened upon the cars. The cars, adapted to receive the airship, are provided with separate supports for the airship, which supports are so arranged that they can easily be adjusted or turned so that while the airship is descending no projecting parts would be likely to cause damage. These supports mounted on the cars, carry beds or girdles composed of sail-cloth or the like, into which the airship is pulled. The anchoring is effected, and the supports, as also the sail-cloth beds, are retained in the raised position by means of tension wires or cables.

In the drawing:—Figure 1 is a side elevation showing an airship on the turntable which serves to receive the cars. Fig. 2 is a front elevation corresponding to Fig. 1, drawn to an enlarged scale. Figs. 3 and 4 show diagrammatically in elevation and plan respectively, the station or berth which consists of the shed and the turntable. Fig. 5 shows the support for the anchor cable in the raised and extended position. Figs. 6 and 7 are detail side and end views of the means for winding up and unwinding the flexible webs or girdles.

55 The shed H, for the airship L, has rail tracks therein which extend in the usual

way as at S, to a turntable D adapted to receive a number of cars 1. The lengths, sizes and relative positions of the cars are adapted to suit each particular airship, and the cars are positively coupled together. On the cars 1 are mounted foot pieces 2 in which the supports 3 are hinged, so that they can be collapsed to lie flat on the cars, or can be raised when required. In the raised position the supports 3 are connected together by transverse rods 4 and retained in this position by the tension ropes 5. The rods 4 carry the sail-cloth girdles 6 adapted to receive the airship L. To prevent the girdles 6 from being raised by the wind, these can be retained in position by tension ropes 7. To pull the airship L downward into the sail-cloth girdles 6, ropes 8 can be employed which engage with the sides of the airship at 9, and are secured to the cars 1 at 10 where winches or the like for the ropes 8 are advantageously provided.

Concentric with the turntable D is a concrete anchoring ring V to any one of a number of attachment points on which the anchoring cable A, attached to the head of the airship, is secured in the known manner (Figs. 3 and 5). The support P, which can be raised and lowered at the end of the railway track on the turntable, serves, when in the raised position, to retain the cable attached to the airship, and to hold the head of the airship at such a level that it can freely swing over the entire apparatus; the supports 3 with the sail-cloth girdles 6 being raised in the meantime. The support P, at the forward end of the railway track, is adapted to be folded in the direction of the arrow (Fig. 5) and to be raised or lowered by a rope gear, or by a motor or otherwise. At the upper end of the support is mounted a roller R over which passes the anchor cable A. The support P is composed of two parts, one extensible in relation to the other by suitable means.

The operation of the device is as follows:—If the airship is to land, then its head is connected to one of the anchoring points V by the cable A, determined by the direction of the wind, so that the airship will stand over the turntable. The turntable D with the cars 1 is then adjusted so that the cars 1 come below the airship. Thereupon support P is adjusted to the necessary height thus bringing the head of the airship to the correct level. The sup-

ports 3 with the sail-cloth girth 6, forming the subject of this invention, are then raised and subsequently retained in position by the ropes 5 and 7. Finally the airship is pulled 5 downward into the girths 6 by means of the ropes 8. After the airship has been fastened on the cars 1, the turntable D is rotated until the railway track thereon is in alignment with the rails S and the cars 1 are run 10 into shed H and the airship is thus berthed.

For the purpose of varying the depth of the girths formed by the sail-cloths 6, the rods 4 to which the ends of the sail-cloth pieces are attached, may be made rotatable 15 in bearings 44 in the ends of rods 4, and for example pawls 34 and ratchet wheels 24 may be provided for holding the rods 4 in any position with the cloths 6 more or less wound around the said rods 4. The ropes 7 also 20 prevent the airship, when resting on the beds, from being pressed against the supports 3.

To prevent the cars 1 from being tilted off the rails guide rollers 12 are provided 25 thereon which engage with rails 13 secured to the turntable D. These rails run parallel to the rails S into the shed H.

Having thus described my invention, what I claim as new and desire to secure by Letters Patent is:—

1. A device for use in berthing airships, comprising cars for the reception of the airship, folding supports mounted on said cars, transverse rods connecting together the 35 folding supports, cloths attached to the transverse rods, the cloths being adapted to be wound and unwound on said transverse rods for the purpose of adjustment.

2. A device for use in berthing airships

comprising a turntable, a railway track 40 thereon, cars running on said railway track, folding supports on said cars, cloths attached to the folding supports, the said cloths forming a resilient bed for the airship, means for anchoring the airship at the 45 required level for its attachment to the cars, and means for attaching the airship to the cars.

3. A device for use in berthing airships comprising cars for the reception of the airship, folding supports mounted on said cars, and cloths attached to said folding supports, the said cloths forming a resilient bed for the airship, means for retaining the folding supports in the raised position, and means 55 for preventing movement of the cloths when receiving the airship.

4. A device for berthing air ships comprising a plurality of cars, a turn-table for the cars, anchoring devices concentric with 60 the turn-table, pivoted means on each side of each car, flexible girths extending between the pivoted means, and tension members for holding the girths and pivoted means with relation to the car and air-ship to be berthed. 65

5. A device for berthing air ships, comprising a turn-table, an extensible head post thereon, a plurality of cars on the turn-table, flexible girths on the cars arranged to be raised and lowered, means for lengthening 70 and shortening the girths and tension ropes to hold the girths in position.

In witness whereof I have hereunto set my hand in presence of two witnesses.

HANS FREIHERR V. SCHLEINITZ.
